VANITY CASE AND ANALOGOUS APPARATUS

Application filed July 18, 1929. Serial No. 379,143.

The invention relates to vanity boxes or analogous apparatus.

It has for its object to provide a device which will be used as an adjunct of the toilet table, make up box or compact and in which various shades or tones of color may be produced for the purpose of testing and predetermining the facial make up of the user in accordance with the various colors, shades, tones, brilliance or intensity of light to which the wearer may be subjected.

The apparatus will also act as an aid in producing any given complexion such as oriental, blonde, brunette, etc., and in accentuating any particular feature or features of the face under varying light or color conditions, both direct and reflected.

A further object of the invention is to provide an apparatus of this description which is exceedingly simple and efficient, and one that is easy to operate and highly ornamental in appearance.

Numerous other objects and advantages will become apparent as this specification proceeds. Referring to the drawings forming a part thereof and in which preferred embodiments of the invention are illustrated:

Fig. 1 is a perspective view of one form of the invention, the parts being in their closed position;

Fig. 2 is a central longitudinal sectional view, with parts in elevation and parts broken out for economy of space. In this view the device is in its open position;

Fig. 3 is a fragmentary sectional view taken at right angles to Fig. 2 and with the parts in their closed position;

Fig. 4 is a plan view of one form of color screen;

Fig. 5 is a perspective view of another embodiment of the invention, the parts being in their open position;

Fig. 6 is a top plan view with parts of the cover members broken away for clearness of illustration;

Fig. 7 is a longitudinal sectional view taken on line 7—7 of Fig. 6; and

Fig. 8 is a cross-sectional view taken on line 8—8 of Fig. 6.

Referring again to the drawings and par-

ticularly to Figs. 1 to 4, the reference numeral 10 designates what might be termed the base and 11 the lamp housing. The lamp housing is hinged to the base at 12.

The base 10 is preferably made in the form of a closed compartment and has a drawer 13 for accommodating cosmetics such as creams, powders, rouge, lipsticks, pencils, lotions, etc.

The lamp housing 11 comprises a frame 14 to which is attached or built integral therewith, the lamp compartment 15. Suitably secured in the upper closed end of the lamp compartment is a socket 16 in which is mounted a light 17 provided with a reflector 18. The lamp compartment and housing may be of any desired shape or suitably decorated to produce a highly ornamental effect when the apparatus is in its closed position as illustrated in Fig. 1. The sides of the lamp compartment may be made of a translucent material and thus provide an ornamental light when the device is not in use.

Suitably mounted in the open end of the lamp housing are rollers 19. The rollers 19 carry a color screen 20 which is particularly illustrated in Fig. 4. The color screen in this instance may be made of silk or other similar material and comprises of series of various tones or shades of colors indicated at 21. The rollers 19 are provided with knobs or buttons 22 outside of the lamp housing in order to facilitate bringing the different tones or shades of the color screen in front of the light.

A mirror 23 is secured to a member 24 which is hinged to the lamp housing at 25. The hinges 12 and 25 may be stiff enough to hold the parts in the most advantageous position for using or other suitable stops or means might be provided for this purpose.

Reference will now be had to Figs. 5 to 8 of the drawings. This form of the invention is adapted particularly to portable use such as in a lady's purse or hand bag.

The reference numeral 30 designates a casing. Hinged at 31 to one end of the casing is a cover 32. This cover is preferably in the form of a boxlike compartment in which rouge may be carried. Hinged at 33 to the

opposite end of the casing is another cover 34 to which a mirror 35 may be secured. Suitable catches indicated at 36 are provided for maintaining the covers in their closed positions.

- The casing 30 is provided with partitions 37 and 38 which define three other compartments. The compartment 39 may be used for powder and 40 for a lip stick or pencil.
- 10 The remaining compartment 41 houses a small battery 42 which is electrically connected with a bulb 43. The current may be turned on or off by a switch indicated at 44. The bulb 43 is provided with a reflector 45.
- 15 The color screen in this embodiment of the invention takes the form of a series of slides 46. The battery compartment 41 has a removable cover 47. The slides 46 are connected to this cover by a pin and slot connection 48. Any individual one of the slides 46 may readily be slid over the reflector or if other tones or shades of color are desired a pair of the slides may be moved over the reflector.
- 20 25 From the foregoing it is thought to be apparent that a set or series of color screens are provided which are readily controllable and used in connection with a source of light so as to cast a color tone or shade on an object or face for the purpose of testing or predetermining facial makeup.

While a color screen of various shades and tones has been illustrated and described it is desired to draw attention to the fact that the 30 desired result might be obtained by using colored lights separately or in combination. It is also desired to point out that other light than electric light might be utilized, for instance, the sun's rays or any other kind of light suitably directed by reflection or otherwise.

The apparatus might readily be made up in other forms than those described and illustrated and numerous changes may be made in 35 details of construction and arrangements of parts without departing from the spirit of the invention or the scope of the appended claim.

We claim:

50 A vanity case or analogous article having in combination, a base, a lamp housing open at its lower end and hinged to one edge of said base, a light supported in the upper part of said lamp housing, a reflector for said light, 55 a pair of rollers mounted adjacent the open end of said lamp housing, and a color screen of various shades and tones carried by said rollers, said color screen being exposed when the lamp housing is swung away from said base and concealed when said lamp housing is closed over said base.

In testimony whereof we affix our signatures.

ROBT. E. DONNELLY.
GEORGE S. JACOB.
